UNITED STATES PATENT OFFICE.

LOYD ELDEN ASHENFELTER, OF ATLANTA, GEORGIA.

TOBACCO-BITER.

1,353,944.

Specification of Letters Patent. Patented Sept. 28, 1920.

Application filed September 11, 1919. Serial No. 323,086.

To all whom it may concern:

Be it known that I, LOYD E. ASHENFELTER, a citizen of the United States, and a resident of Atlanta, in the county of Fulton and State of Georgia, have invented certain new and useful Improvements in Tobacco-Biters, of which the following is a specification.

My invention is an improvement in tobacco biters, and has for its object to provide a device of the character specified for tobacco chewers' use adapted to be connected with the plug, for severing when desired a piece of tobacco of suitable size for a chew.

In the drawings:—

Figure 1 is a front view of the improved biter in opened position;

Fig. 2 is a side view of Fig. 1;

Fig. 3 is a front view, showing the biter closed;

Figs. 4 and 5 are sections on the lines 4—4 and 5—5, respectively, of Fig. 1;

Fig. 6 is a plan view of the cover plate 25 of the blade with the impaling spike unfolded;

Fig. 7 is a similar view of the blade;

Fig. 8 is a plan view of the body of the blank from which the body of the biter is 30 formed; and

Fig. 9 is a plan view of one of the blanks for the guide.

In the present embodiment of the invention, a suitable body or frame is provided, 35 cut or stamped from a blank of metal of suitable size. This blank shown in Fig. 8 consists of a body portion 1 of elliptical form and having a center elliptical opening 2, and the body has wings 3 at its opposite 40 side, the side wings being at approximately the center of the body. This blank is bent to form spaced approximately parallel clamping jaws 4 and 5 spaced far enough to receive the end of the plug between them 45 and extending at approximately right angles to the body. Both jaws 4 and 5 have their extremities curved outwardly, as shown at 6, to facilitate the insertion of the plug, and the opening 2 is so arranged that it will 50 extend well into the jaw 4, and considerably farther than into the jaw 5.

The wings 3 are bent to form channel-shaped guides, the said guides extend inwardly and facing each other, and the blade 55 7 shown in Fig. 7 is arranged to move in these guides. This blade, as shown, is pro-

vided with lugs 8 at its upper edge, three in the present instance, namely, a center and two lateral lugs, and with longitudinally-extending slots 9 near its side edges. The 60 side edges 10 of the blade are bent outwardly, as shown more particularly in Figs. 1 and 5, to lie in the same plane, and these outwardly bent edges engage channel-shaped guides 11, which are held in the guides 3, 65 the said guides 11 serving as bushings, and also as extensions for the guides 3. As shown in Figs. 1 and 2 the guides 11 may extend well above the guides 3 so that they will still support the blade, when the blade 70 is entirely lifted above the guide 3. The blade, as shown in Figs. 1, 3 and 5 is curved transversely, to cut a bite of suitable size from the plug, and pins 12 extending transversely of the guides 11 intermediate their 75 ends, which engage the slots 9 to limit the movement of the blade in each direction with respect to the guides.

A plate 13 is connected with the top of the blade for holding the same in proper 80 position and for providing a finger piece for convenience in manipulating the blade and this plate has slots 14 for receiving the lugs 8 of the blade. The said lugs after passing through the slots are upset to hold 85 them firmly in place. Referring to Fig. 2, it will be seen that the plate 13 is of larger radius than the curve of the blade so that said plate extends beyond the blade at the 90 convex faces in either direction. At the center of its curved edge the blade has a spike 15, which is bent downwardly at right angles to the blade, and which is adapted to impale the plug, to lock the plug and biter together during the time when not 95 in use and when it is stored in the pocket of the user.

Each of the wings 3 of the blank from which the body is formed is recessed longitudinally at its free edge, as shown at 16, 100 and lugs 17 extending outwardly from the plane of the blade are provided at each end of these cut-away portions 16.

The guides 11 have laterally extending lugs 18 at that edge which will be adjacent to the 105 cut-away portion 16 when the guides are in place and these lugs 18 move in the cut-away portions 16 between the lugs 17. The arrangement thus permits the guides 11 to telescope into the guides 3. The movement 110 of the guides 11 is limited however by the engagement of the lug 18 with the lug 17.

The ends of the jaws 4 and 5 are rounded, as shown, and the opening 2 is so arranged with respect to the body 1 of the frame that it will extend well beyond the cutting edge 5 of the blade, thus permitting the user to observe through the opening the amount of tobacco that will be cut when the blade is operated.

In operation the plug is slipped between 10 the jaws 4 and 5, the blade at this time being in the position shown in Fig. 1, and after it is properly positioned, the plate 13 is pressed downwardly driving the blade through the 15 plug and the amount cut off by the blade may be observed through the opening 2 from above the jaw 4 or from the front of the cutter, if desired. The spike 15 will impale the plug and will hold it firmly during the cutting. After a chew has been 20 taken from the plug the parts are left in the position shown in Fig. 3, the biter being firmly anchored to the plug by the impaling spike 15. As a bite is severed the plug is 25 impaled by the spike, thus anchoring the biter to the plug until it is again used. When again used the blade is raised and the biter is shifted for a new bite.

I claim:

1. A tobacco biter comprising a holder 30 for the plug consisting of a frame having a body and laterally extending jaws for receiving the plug between them, the body being open to permit of inspection of the plug, said body having at each side of the 35 opening a channel-shaped guide, each guide consisting of telescoping sections having a limited movement away from each other, a transversely curved blade having outwardly bent edges to engage within the guides, said blade and guides having means for limiting 40 their movement with respect to each other, a plate serving as a finger piece secured to the top of the blade and extending beyond the blade away from the body of the plug receiving frame, said plate having a depend- 45

ing spike for impaling the plug during and after the cutting.

2. A tobacco biter comprising a holder for the plug consisting of a frame having a body and laterally extending jaws for receiving the plug between them, the body being open to permit of inspection of the plug, said body having at each side of the opening a channel-shaped guide, each guide consisting of telescoping sections having a limited movement away from each other, a transversely curved blade having outwardly bent edges to engage within the guides, said blade and guides having means for limiting 50 their movement with respect to each other, a plate serving as a finger piece secured to the top of the blade and extending beyond the blade away from the body of the plug receiving frame, said jaws having their extremities curved outwardly to facilitate the 55 entrance of the plug.

3. A tobacco biter comprising a holder for the plug consisting of a frame having a body and laterally extending jaws for receiving the plug between them, the body being open to permit of inspection of the plug, said body having at each side of the opening a channel-shaped guide, each guide consisting of telescoping sections having a limited movement away from each other, a transversely curved blade having outwardly bent edges to engage within the guides, said blade and guides having means for limiting 60 their movement with respect to each other, a plate serving as a finger piece secured to the top of the blade and extending beyond the blade away from the body of the plug receiving frame, said jaws having their extremities curved outwardly to facilitate the 65 entrance of the plug.

LOYD ELDEN ASHENFELTER.
